PUZZLE TOY

Todd M. Rostock, 219-36 67th Ave.,
Bayside, N.Y. 11364

Filed Apr. 9, 1973, Ser. No. 349,039

Term of patent 14 years

Int. Cl. D21—01

U.S. Cl. D34—15 M

FIG. 1

FIG. 2

FIG. 1 is a perspective view of a puzzle toy, showing my new design; and

FIG. 2 is a similar view with the component parts in the position of solution.

I claim:

The ornamental design for a puzzle toy, substantially as shown.
